US00D617132S

(12) **United States Design Patent**
Wang

(10) **Patent No.:** **US D617,132 S**
(45) **Date of Patent:** **** Jun. 8, 2010**

(54) **WATER COOLER**

(75) Inventor: **Chun Yen Wang**, El Paso, TX (US)

(73) Assignee: **MTN Products, Inc.**, Pomona, CA (US)

(**) Term: **14 Years**

(21) Appl. No.: **29/343,094**

(22) Filed: **Sep. 8, 2009**

(51) **LOC (9) Cl.** **07-01**

(52) **U.S. Cl.** **D7/306; D7/313; D7/311**

(58) **Field of Classification Search** **D7/300, D7/306-311, 312, 313; 222/185.1, 146.6**
See application file for complete search history.

(57) **CLAIM**

I claim the ornamental design for the water cooler, as shown and described in the drawings.

DESCRIPTION

FIG. 1 is a front and side perspective view of one preferred embodiment of the water cooler of the present invention;

FIG. 2 is a front perspective view of the water cooler shown in FIG. 1;

FIG. 3 is a top-front perspective view of the water cooler shown in FIG. 1;

FIG. 4 is a left-side perspective view of the water cooler shown in FIG. 1;

FIG. 5 is a rear perspective view of the water cooler shown in FIG. 1; and,

FIG. 6 is a top-rear perspective view of the water cooler shown in FIG. 1.
